[57] **CLAIM**

The ornamental design for a fingernail clipper or the like, as shown and described.

DESCRIPTION

FIG. 1 is a top plan view of a fingernail clipper or the like showing my new design;

FIG. 2 is a left side elevational view, the right side being a mirror image thereof;

FIG. 3 is a front elevational view thereof;

FIG. 4 is a bottom plan view thereof;

FIG. 5 is a rear elevational view thereof;

FIG. 6 is a top plan view of the design with the lever in a raised position; and

FIG. 7 is a left side elevational view of FIG. 6.
